UNITED STATES PATENT OFFICE.

EDWARD E. CLEMENT, OF WASHINGTON, DISTRICT OF COLUMBIA.

TELEPHONE-EXCHANGE SYSTEM.

1,109,620.

Specification of Letters Patent.

Patented Sept. 1, 1914.

Application filed February 26, 1908. Serial No. 417,976.

To all whom it may concern:

Be it known that I, EDWARD E. CLEMENT, a citizen of the United States, residing at Washington, in the District of Columbia, 5 have invented certain new and useful Improvements in Telephone-Exchange Systems, of which the following is a specification, reference being had therein to the accompanying drawing.

10 My invention relates to telephone exchange systems and it consists of the combinations and arrangements herein described and claimed.

15 My invention is particularly applicable to those telephone systems of the so-called full automatic or semi-automatic types in which the connective links consist of trunk circuits provided with automatic switches for interconnecting said circuits and for completing the connection with a wanted subscriber. The invention lies in the improvement 20 of the means for selecting and connecting a calling line with the first connective trunk or link circuit.

25 In most of the devices for a similar purpose heretofore patented there are numerous faults, which in practice interfere with the proper working of the system, besides causing occasional delay and trouble both to 30 those whose duty it is to keep the apparatus in good order and to the subscribers themselves. Thus in most of the systems heretofore proposed, the release of the primary switching mechanism can only be brought 35 about after the calling line has been picked up and connected to the first trunk. The selection and connection of a calling line is usually accomplished by the mere act of closing a line circuit when a subscriber re-

40 moves his receiver. But it may happen that the subscriber will open his line circuit again before the switch has effected the desired connection. In such a case the switch is liable to be stopped at the moment that 45 the line circuit is broken and may be in a position where it is entirely disconnected from any actuating circuit whatever.

One object of my invention is to provide 50 means whereby the selector switch may be restored to its original position even if the

calling subscriber should open his line circuit during the operation of connection and before the switch has come to rest on the terminals of the calling line.

Another object of my invention is to provide means for distributing the incoming calls successively among the idle trunks, thus distributing the load evenly among all of the operators of the exchange.

The two main features of my present invention consist in the use of a pilot switch responsive to the closing of a calling subscriber's line-circuit which, in turn, is capable of operating one of a group of primary selector switches; and in the employment of a distributing switch which works in connection with the pilot switch and causes the incoming calls to be automatically landed on successive idle trunks. In order to carry out my present invention I 60 employ, in connection with these switches, ordinary relays. The pilot switch which forms a distinctive feature of my invention has a test wiper having a rotary movement but not a vertical movement. It has another wiper having both a vertical and a rotary movement to connect with the contacts leading to a calling line. The pilot switch in its movements transmits a series 65 of impulses to the selector switch and the two switches step around and up simultaneously and come to rest practically at the same time on the contacts leading to the calling line. The manner in which this is accomplished, as well as the manner in 70 which the incoming calls are evenly distributed and the switch is restored, will be fully explained in the body of the specification.

75 My invention is illustrated in the accompanying drawings in which:

Figure 1 shows the subscribers' line terminals, the primary selector switches and trunk circuits. Fig. 2 shows part of a central station manual connective circuit arranged to coöperate with the trunk circuits 95 shown in Fig. 1. Fig. 3 shows part of a central station automatic connective circuit arranged to coöperate with the trunk circuits shown in Fig. 1. Fig. 4 is a diagrammatic view of a first selector switch circuit, 100

a second selector switch circuit and a connector switch circuit. Fig. 5 is a side view of a pilot switch. Fig. 6 is a plan view of the rotary test wiper and test contacts. Fig. 5 is a circuit for a modified form of pilot switch. Fig. 8 is a detail view showing a structural embodiment of the modified form of pilot switch shown diagrammatically in Fig. 7.

Referring now to Fig. 1, I have shown therein the terminal apparatus of three line circuits leading to the subscribers' stations A, A' and A''. This terminal apparatus consists of the cut-off relays N, N' and N'', and the line relays M, M' and M'' together with the contacts controlled by these relays. The line relays when actuated are adapted to set in motion a pilot switch P and through the medium of the switch D to effect the connection of a calling line with an idle trunk.

The primary selector switches S, S', etc., are preferably of the same general type as that shown in my pending application Serial No. 399,284, filed October 26, 1907. A brief description of one of these switches will suffice.

In general the switch consists of a movable shaft s having both a rotary and a vertical movement. The rotary movement is effected by the magnet R while the vertical movement occurs when the magnet V is energized. The means by which these two movements is accomplished is fully set forth in the application referred to, and the actuating circuits will be fully traced hereinafter.

The pilot switch P is of somewhat similar construction. The lower wiper w is a test wiper and its engagement with the contact c causes the switch to stop rotating when it reaches a vertical row of contacts c' leading to the calling line. This switch is illustrated in Figs. 5 and 6. It consists in general of a rectangular frame 300 inclosed within which are the operating parts. These comprise a vertical magnet M', a rotary magnet M' and a release magnet R''. The vertical magnet is provided with a pivoted armature 301 arranged to actuate a pawl 302 for stepping up the shaft 303 by its engagement with cylindrical ratchet 304. The rotary magnet M' has also a pivoted armature 305, with an extension 306 adapted to rotate the shaft 303 through the engagement of an actuating pawl 307 with a ratchet 308. The release magnet R'' is arranged to effect the restoration of the switch to its normal position by the withdrawal of the dog 309 from its engagement with the cylindrical magnet 304. The switch is provided with a contact bank having vertical rows of contacts adapted to be engaged by a wiper w' successively as the shaft is stepped up. Immediately below the

bank of contacts engaged by the wiper w' is a single row of contacts c adapted to be engaged by a wiper w. This wiper is mounted on a sleeve or ring 314 carried by the shaft and splined to the latter. The sleeve is held down upon a bearing ring 315 by means of a spring 316, the latter also serving as a circuit terminal. When the shaft is rotated the sleeve 314 is rotated with it and carries the wiper so around into successive engagement with the test contacts c. When the shaft is raised vertically the sleeve is held down by the spring and the wiper w remains in engagement with the contact on which it last rested before the upward movement of the shaft.

During the rotary and the vertical movements of the pilot switch, impulses are being sent to the selector switch of the first idle trunk which follows the movement of the pilot switch and, when the latter stops, the wipers of the selector switch rest upon the contacts leading to the calling line. The selection of an idle trunk is accomplished as before stated through the medium of the switch D in the manner hereinafter explained.

The circuits controlled by the various relays shown in Fig. 1 are clearly indicated in the drawing. These circuits will be fully traced in the explanation of the operation of the system.

In Fig. 2 I have shown the trunk as terminating at a plug P. In this figure are also shown the supervisory lamps L and L' and calling lamp L''. The jacks J are for the purpose of completing the connection with a wanted subscriber's line on the insertion by the operator of the plug P. T' indicates the operator's set.

Fig. 3 shows part of the central station automatic connective apparatus, including the operator's set T' connected to the listening key K, the signal lamp L' and the impulse sending device I'.

Referring now to Fig. 4, I have shown therein a first selector switch denoted in general by X, a second selector switch Y, and a connector switch Z. These switches and their circuits are of the well known Strowger type and are described as to their mechanism in the patents to Keith and Erickson Nos. 815,176 and 815,321, March 13, 1906. They form no part of the present invention except in so far as they are necessary to show a complete operative system. It will be understood that any other switches adapted to complete the connection of the trunk circuit shown in Fig. 1 with a called subscriber's line (such as that shown in my application 399,284, filed Oct. 26, 1907) might be substituted for those herein described, the particular invention in this case lying in the means by which a calling line is picked up.

and connected with the operator's trunk circuit. The description of the various actuating circuits of Fig. 4 will be fully set forth in the explanation of the operation of the system.

Having thus described the apparatus used in my improved telephone exchange system I will show in detail how calls may be answered and the connections made from a calling to a called subscriber.

Let us assume that the subscriber at station A' desires to talk with another subscriber whose number is 2312. When he takes down his receiver his line circuit 1—2 is closed and the line relay M' is actuated, the actuating current being from battery B, through 3, 4, M', 5, 1, through the subscriber's telephone, back on line-wire 2 and to ground through the armature 6 of the cut-off relay N'. Thereupon the armatures 7, 8 and 9 of the line relay M', pull up. The closing of the contacts 7 and 10 causes the energization of the relay E, the energizing current being from battery, through 3, 4, 7, 10, 11, E, 12, through the closed contacts 13 and 14 to ground. Thereupon the armatures 15, 16 and 17 of the relay E are attracted. The pulling up of the armature 17 of the relay E connects battery with the arm d of the switch D over the following path: battery, 18, 19, 17, 20, 21, 22, 23, 24, d. The arm d is shown resting on a contact connected with an idle trunk. Only three contacts of this set are shown connected to their respective trunks in order to avoid complexity of circuits in the figure but it will be understood that each one of the contacts is connected with the master relay corresponding to R^a belonging to its particular trunk. One of the connected switch arms d, d', d², is always resting on a contact leading to a relay of an idle trunk and the two sets of arms d, d', d² and d³, d⁴ and d⁵, are carried by the same shaft and are arranged one above the other, their respective contacts being similarly arranged. The pulling up of the armature 16 of the relay E energizes the rotary magnet R^p of the pilot switch P^s intermittently, current flowing by the following path: battery B, 18, interrupter I, 25, 16, 26, 27, 28, 29, 30, R^p and ground. The intermittent current due to the interrupter I causes the relay R^p to rotate the shaft of the pilot switch P^s one step at each impulse.

We will assume that the station A' is one of a group of ten stations each connected to its respective contact in the fourth row and all of the group having a common connection with the test contact c associated with the fourth row. Current having been supplied to the magnet R^p, the latter will cause the pilot switch P^s to rotate in the manner described, and when the test wiper w en-

gages the contact c, the relay F is energized, 65 breaking the energizing circuit of the magnet R^p at the contacts 27, 28, thereby stopping the switch at the fourth row. The energizing current of the relay F is from, battery B, through 3, 4, 9, 31, 32, c, w, 33, F, 70 and ground.

At the same time that the magnet R^p is being operated an intermittent current is also being sent through the winding of the rotary magnet R belonging to the first idle 75 trunk. I have assumed that none of the trunks are busy and have therefore shown the small arm d of the distributing switch as resting on the first contact leading to the relay R^a of the trunk circuit 100—101. This relay therefore becomes energized at the first closure of the contacts 17 and 20 which connect battery with the arm d by the path already traced, the remaining portion of the energizing circuit being through the wire 34, 80 relay R^a and to ground. The energization of the relay R^a closes the circuit of the magnet R through its armature 35. The energizing circuit of the magnet R may now be traced from the wire 29, from which the intermittent current to the magnet R^p is supplied, thence by conductor 36, 37, 35, 38, R and ground. The magnet R therefore is actuated simultaneously with the magnet R^p and causes the rotation of the shaft s of the 95 switch S to the fourth row of contacts.

The movement of the armature 27 of the relay F breaks the energizing circuit of the two magnets R^p and R and completes the circuit of the vertical magnet V^p of the pilot 100 switch and the vertical magnet V of the selector switch S. The energizing circuit of the former may be traced from the contact 27, through 39, 40, 41, 42, V^p and ground, and that of the magnet V from the branch 105 wire 42 leading from the wire 41, 43, contact 44 of relay R^a, 45, magnet V and ground. The intermittent current placed on the vertical magnet V^p of the pilot switch causes the shaft of the latter to be stepped 110 vertically one step for each impulse, the wiper w' of the switch engaging the contacts successively during its movement. At the same time that the magnet V^p is stepping up the switch P^s, the magnet V is stepping up the switch S, each movement of the pilot switch being accompanied by a corresponding movement of the selector switch. When the wiper w' engages the second contact 2° of the row, the energizing circuit of 120 the relay H is completed over the following path: battery, 3, 4, 8, 46, 2°, w', 47, H and ground. The pulling up of the armature 40 of the relay H cuts off the vertical magnets V and V^p and the switches therefore stop 125 with their wipers resting on the second contacts of the row in their respective contact banks. The actuation of the armature 22 of

the relay H disconnects battery from the arm d, deenergizing the trunk R^a, whose armatures 35 and 44 retract, thereby cutting off the vertical and rotary relays. The extension 48 of the line-wire 1 is now connected to the trunk conductor 101 by means of the multiple conductor 50, contact 1c, wiper 1w, while the extension 49 of the line-wire 2 is connected to the trunk conductor 100 by means of the multiple wire 51, contact 1c' and wiper 1w'.

When the wipers of the selector switch S come to rest on the terminals of the calling line, the cut-off relay N' is energized in series with the sleeve relay R^c, the energizing current being from battery, through 18, 52, R^c, 53, 54, 55, trunk conductor 100, 1w', 1c', 51, 49, N' and ground. The actuation of the cut-off relay N' closes the contacts 5 and 6 upon the extensions 48 and 49 at the same time breaking the circuit of the line relay M'. Part of the current through the sleeve relay R^c flows over the sleeve side 2 of the subscriber's line, through his instrument, and back upon the tip side 1, through the extension 48, 50, 1c, 1w, 101, 56, 57, 58, tip relay R^b and to ground. The actuation of the armature 59 of the relay R^c places current on the relay R^d, the energizing circuit being from the wire 52 connected to battery as already traced, 59, 60, 61, d², 62, R^d and ground. The movement of the armature 14^a of the relay R^d actuates the magnet R^a, current flowing from the commutator I, through 15^a, 14^a, 16^a, R^a and ground. At each impulse the magnet R^a steps the switch D around one step. The first step brings the arms d and d² on the contacts leading to the next trunk 102 and 103. If this trunk should happen to be busy its sleeve relay R^c will be energized and battery current will be supplied to the relay R^d through the wire 63, and the armature 14^a being still up, the magnet R^a will be again energized and the switch arms will take another step and continue to step around until the arm d² fails to find a contact connected with battery, i. e. until it finds an idle trunk. It will thus be seen that by this method of bringing in the idle trunks the calls are distributed evenly among the operators of the exchange and that no one operator is over-burdened with work while others may be idle.

Having now described the manner in which the in-coming calls are picked up and put on idle trunks I will show the operation of the release mechanism in case a calling subscriber should hang up his receiver before the pilot and selector switches have to come to rest on the contacts of the calling line. In the ordinary process of calling, this contingency could hardly happen because the selection and connec-

tion of a calling line with a trunk takes place very rapidly. It might however happen in case a subscriber should accidentally lift the switch-hook for an instant. An inspection of the drawing will show that the pilot switch is provided with a pair of contacts 64, 65 which are kept normally apart by means of an insulating cam 66 at the foot of the shaft. At the first rotary motion of the latter the two contacts 64, 65 are closed and battery is put upon the contacts 67 of the relay F and upon the contacts 68 and 69 of the relay H. When therefore these relays pull up they are locked through their respective contacts 67 and 68. Let us assume that the subscriber who had closed his line circuit has opened it again before the wiper w' of the pilot switch P' has come to rest on the contacts leading to the calling line. The breaking of the line circuit deprives the line relay M' of current, allowing its armatures to retract. The retraction of the armature 7 breaks the energizing circuit of the relay E, already traced. The retraction of the armature 15 of the relay E completes the energizing circuit of the release magnet R^e which releases the switch P^s and restores it to its normal condition. This circuit may be traced from battery, through the contacts 64, 65, armature 15 of relay E, 70, 71, R^e and ground.

The restoration of the switch S in case a subscriber hangs up before the wipers come to rest on the contacts leading to the calling line, is accomplished as follows: Near the end of the switch shaft s is a collar 72 provided with a socket 73 arranged to receive the bent end of a contact spring 74. At the first rotary movement of the switch the collar 72 exerts a camming action on the bent portion of the spring and forces the spring 74 into engagement with the spring 75, the latter being connected to ground through the resistance 76. When the subscriber hangs up he deenergizes the relay E for the reason already explained and the retraction of the armature 17 cuts off the energizing circuit of the relay R^a, which as before stated is through the switch arm d. The retraction of the armature 54 of the relay R^a now completes an energizing circuit of the sleeve relay R^c from battery, through 18, 52, R^c, 53, 54, 55, trunk conductor 100, 74, 75, 76 and ground. The armature 59 of the relay R^c engaging its front contact 60 completes the energizing circuit of the release magnet R^e through the armature 77 of the tip relay R^b, R^e, R^b and ground. This restores the switch to its original position and takes the ground off from the relay R^e by the opening of the contacts 74, 75. It will be noted that while the switch S is making its rotary movement the actuating circuit of the relay

R^e will be made through the closed connections 74, 75 in case the calling subscriber hangs up his receiver and the armature 54 of the relay R^e falls back. When the 5 switch makes its first vertical movement its lower wiper passes over contacts which are grounded through the cut-off relays of the respective lines, and if a calling subscriber should then hang up his receiver the relay 10 R^e would be energized by current through the cut-off relays of the respective lines instead of through the contacts 74 and 75 which are then open.

After the impulses have all been sent in 15 and the calling line has been connected with an idle trunk the relay H is energized and locked in the manner already stated, and the movement of its armature 69 closes the energizing circuit of the release magnet R^e , this 20 circuit being as follows: battery, 18, 64, 65, 79, 69, 80, 71, R^e and ground. This restores the pilot switch which drops down and turns back to zero position, opening the contacts 64, 65 in the locking circuits of the 25 relays F and H , restoring them to their normal condition. The pilot switch is now ready for any other call that may come in.

As has been before stated the connection of the trunk 100, 101 with the calling line 30 results in the energization of both the sleeve relay R^e and the tip relay R^b . The movement of the armature 77 of the relay R^b prevents the energization of the release relay R^e . The tip relay R^b is now under control of the calling subscriber and is deenergized when he hangs up his receiver.

Considering now the use of the manual connective circuit as illustrated in Fig. 2 it 40 will be observed that on the pulling up of the armature 81 of the relay R^e battery current is supplied over the wire 18 and through the armature 81, over conductor 82, armature 83 of the relay R^e , 84, D^s , resistance r and ground. The operator observing 45 the lighting of the signal lamp presses her listening key K thereby closing the contacts 85—86, 87—88, and connecting the telephone set T^o and at the same time closing the springs 89—90, thereby shunting the 50 lamp L^e and its resistance r , and causing the current to flow through the conductor 91, relay R^e and ground. The relay R^e thereupon pulls up and locks through the 55 armature 83 at the same time cutting off the signal lamp which goes out. The operator having learned the number inserts the plug 60 P into the jack J and thereupon the relay R^b is energized, current flowing from battery, through 92, R^b , 93, 200, p' , j' , cut-off relay N^o and ground. The pulling up of 65 the armature 94 of the relay R^b puts current onto the supervisory lamp L^x , while the actuation of the cut-off relay N^o closes the subscriber's line circuit onto the extensions leading to the jack. The operator now presses

her ringing key K^r , thereby cutting off the plug P from the trunk circuit and connecting the ringing generator G^r .

When the subscriber answers, the supervisory relay R^s is energized in series with 70 the relay R^b current flowing through the latter as already traced and over the sleeve side 95 of the subscriber's line, through the telephone and back upon the tip side 96 of the subscriber's line and thence by conductor 201 through the relay R^s and to ground. The actuation of the relay R^s extinguishes the supervisory lamp L^x through the pulling up of the armature 97.

After conversation has ended and the calling subscriber hangs up his receiver the tip relay R^b immediately lets go, the sleeve relay R^e being still energized in series with the cut-off relay N^o . The retraction of the armature 77 of the relay R^b completes the 80 circuit of the release magnet R^e in the manner already described which when actuated restores the switch S to its normal position. The breaking of the actuating circuit of the sleeve relay R^e causes it to fall back thereby 85 restoring this part of the connective circuit to its original condition. The retraction of the armature 98 of the relay R^b causes the lighting of the supervisory lamp L , the current for the latter being traced from battery, 90 through 92, 94, 99, 98, 102, L and ground.

When the called subscriber hangs up his receiver, his line circuit is broken, the relay R^s falls back thereby completing the circuit 100 of the supervisory lamp L^x . On observing the clearing out signals the operator withdraws the plug P from the jack J . This breaks the actuating circuit of the relay R^b already traced and it lets go, thereby breaking 105 the supervisory lamp circuits and restoring this part of the connective circuit to its normal condition. It will be noticed that even after the relay R^e has become deenergized, the lamp L will continue to burn because of current through the wire 99, and the same current controlled by relay R^b will be communicated to wire 61 and so cause the trunk 100—101 to test busy until the plug P is finally pulled. These provisions are important in case the called subscriber 110 leaves his receiver off.

It will also be understood that the usual means for testing a wanted subscriber's line is provided in connection with the operator's set T^o and the key K^r .

Referring now to Fig. 3 I have shown therein a lamp signal operated in a similar manner to that already described in connection with Fig. 2. I will now describe the means by which the operator completes the 120 connection between the calling and the called subscriber. In the figure I have represented the operator's sending device diagrammatically at I^s . It is to be understood however that this sending device may be in any form 125

so long as it is capable of sending a predetermined number of impulses over either side of the line.

The number which I have assumed to be wanted by the calling subscriber is 2312. The operator first sends two impulses over the tip side of the trunk 201. These current impulses may be traced from the battery, through 103, K¹, 201, switch arm x², 105, relay D^x, 106, ground. Thereupon the relay D^x pulls up closing the contacts 107 and 108, and completing the energizing circuit of the vertical magnet V^x. The energizing circuit of the magnet V^x is from battery, through 18, 109, 110, V^x, 111, 112, 113, 107, 108. The two impulses upon the vertical magnet V^x causes the shaft S^x of the switch, together with its wipers to step up to the second row of contacts connected with a group of ten trunks leading to second selector switches. The operator now sends one impulse over the trunk conductor 200 by pressing the key K². This impulse causes the operation of the relay E^x, current flowing by the following path: battery, 103, K², 200, switch arm x³, 114, E^x and ground. The pulling up of the armature of the relay E^x closes the contacts 115, 108, thereby completing the energizing circuit of the relay U^x, the energizing circuit being from battery, through 18, 109, U^x, 115, 108 and ground. The actuation of the relay U^x momentarily opens the contacts 112, 113 and closes the contacts 113, 116. The changing of these contacts 112, 113 and 116 produces no result at present and their use will be explained later. When the switch U^x retracts, the arms x¹, x², x³ and x⁴ of the side switch are moved to the second contact. The moment the switch arm x¹ reaches its second contact, battery current is supplied to the rotary vibrating magnet R^x, the actuating current being from battery, through 18, 109, 110, 117, R^x, 118, x¹ and ground. This magnet continues to vibrate and each time it pulls up it rotates the wipers of the switch one step. The test wiper t³ of the switch passes over the contacts s³ successively until it finds an idle trunk. As the wiper t³ passes over contacts leading to busy trunks the relay U^x will be energized by current from battery through 18, 109, U^x, 119, x⁴, release relay W^x, 120, t³, s³, and to ground through the corresponding first selector switch of each busy trunk by way of the multiple terminals corresponding to s³, back through the release relay corresponding to W^x and to ground, the switch arm corresponding to x⁴ of the busy selector switch being of course upon its third contact. It will be observed that this circuit includes the relay U^x and the test relays W^x and the corresponding test relay in the busy switch in series. The relay U^x being high-wound will operate on this circuit while the other two relays will not.

When an idle trunk is found this test circuit is broken since the wiper t³ of the first selector switch is no longer grounded. The energizing circuit therefore of the relay U^x is broken and when it retracts the arms x¹, x², x³, x⁴ of the side switch are moved to their third contact. The movement of the armature x¹ breaks the actuating circuit of the rotary magnet R^x stopping the wipers t¹ and t² on the contacts s¹ and s² of an idle trunk leading to a second selector. The operator now sends in three impulses over the tip trunk conductor 201 and through the connected trunk conductor 203. These three impulses cause the relay D^y to pull up three times, actuating current being from battery, to trunk 203, over the path already traced, thence through y², 121, D^y, 122, and ground. The pulling up of the relay D^y closes the contacts 123 and 124. This energizes the vertical magnet V^y, the energizing current being from battery B, through 18, 125, 126, V^y, 127, 128, 123, 124 and ground. The actuation of the vertical relay V^y causes the switch shaft S^y to step up to the third row of contacts. The operator now sends in one impulse over the trunk conductors 200 and 202. This impulse operates the relay E^y through the switch arm y³ and conductor 129. The pulling up of the armature of the relay E^y closes the contacts 130 and 124, thus actuating the relay U^y the energizing current of the latter being from battery, through 18, 125, U^y, 130, 124 and ground. The retraction of the relay U^y as in the case of the first selector switch X causes a movement of the arms y¹, y², y³ and y⁴ to their second positions. This energizes the rotary magnet R^y in precisely the same manner as its corresponding magnet R^x is energized and the shaft S^y is now stepped around to pick out an idle trunk leading to the connector switch Z. The test wiper t⁴ passes over the contacts s⁴ and the relay U^y is energized until the idle trunk is found, at which time it lets go and moves the side switch arms y¹, y², y³ and y⁴ to their third position. The subscriber is now connected to a trunk leading to a connector switch containing the contacts of the wanted line. The operator now sends one impulse over the trunk conductors 201, 203 and 205. The relay D^z is operated, the energizing current being from the trunk wire 205 through the relay and by the conductor 131 to ground. The pulling up of the armature of the relay D^z closes the contacts 132 and 133 thereby energizing the vertical magnet V^z the energizing circuit of the latter being from battery, through 18, 134, V^z, 135, switch arm z¹, 136, contact 137, 138, 132, 133 and ground. Thereupon the wiper is stepped up to the first row which contains the terminals of the wanted line. The operator now sends one impulse over the connected trunks 200, 202 130

and 204. This energizes the relay E^z . This relay thereupon pulls up, the movement of its armature closes the contacts 189, 183 and energizes the relay U^z in the same manner as heretofore described. On the retraction of this relay the arms z' , z^2 , z^3 , z^4 are moved to their second positions and the movement of the arms z' cuts off the vertical magnet and connects the rotary magnet R^z . The operator now sends two impulses over the connected trunks 201, 203, 205. This actuates the rotary magnet R^z which steps the switch shaft S^z around two steps bringing its wipers t' , and t^3 into engagement with the contacts c' , and c^8 leading to the wanted line. The operator now sends a final impulse over the conductors 200, 202, and 204. The relay D^z is actuated and again closes the actuating circuit of the relay U^z . It will be remembered that the switch arms z' , z^2 , z^3 and z^4 are now in their second positions.

The actuation of the relay U^z closes the springs 140 and 141 and if the called line is busy a test circuit is established as follows: battery B, 134, 142, release relay W^z , 143, 144, 141, 140, 145, t^4 , 146, t^1 , c^7 , and to the multiple terminals of the wanted line. If the wanted subscriber was the calling subscriber of the now busy line this test circuit thus traced to his multiples would be continued to ground through the tip relay of the first trunk corresponding to the relay R^b . If the called subscriber was also the called subscriber on the busy line the test circuit would be continued through the contact corresponding to the contact c^7 , and back upon the tip side of the connector switch and to ground through the relay F^z .

The energizing circuit of the release relay W^z being thus completed this relay is actuated and the pulling up of its armature 170 grounds the release magnet Y^z which restores the connector switch to its original position. The disengagement of the wipers t^7 and t^8 from their contacts c^7 , c^8 , opens the circuits of relays F^z and G^z , the latter then falling back, and the former remaining disabled. It should be noted that these two relays constitute the tip and sleeve battery supply relays respectively for the called line, corresponding to the battery supply relays R^b and R^c of the calling line. Relay G^z therefore derives current through the cut-off relay, but relay F^z receives no current until the call is answered. The relay O is disabled through the opening of the contacts 165, 166 when the shaft reaches its lowest position. This relay becomes energized through the energizing of relay F^z when the called subscriber answers.

The calling subscriber may be informed of the busy condition of the wanted line by any of the ordinary means. Thus a "busy back" may be automatically connected to the line. When the calling subscriber hears

the busy back he hangs up his receiver thereby deenergizing the tip relay R^b of the trunk circuit 100, 101. The retraction of the armature 98 of the relay R^b puts a simultaneous impulse on both trunk wires 200 and 201. This impulse comes from battery B, through 18, 52, 59, 60, 61, 190, 98, and 102, to the trunk wire 201 and over the same path to armature 98 and thence by wire 99 to trunk 200. These impulses cause the tip relays D^x , D^y , and D^z and the sleeve relays E^x , E^y and E^z to operate simultaneously. The closing of the contacts 172 and 171 of the relays D^z and E^z respectively causes the energization of the relay W^y , the energizing circuit being from battery through 134, 142, W^z , 143, 171, 172, 173, s^6 , t^6 , 174, W^y , 175, Y^4 and ground. The pulling up of the armature 176 of the relay W^y closes the contacts 177 and 178. This causes the actuation of the release magnet Y^y which restores the switch Y. In a similar manner the energizing circuit of the release relay W^x is completed from battery, through 18, 125, Y^y , 179, 150, 181, s^3 , t^3 , 120, W^x , x^4 and ground. The pulling up of the armature 182 of the relay W^x closes the contacts 183, 184 and causes the actuation of the release magnet Y^x , the actuating circuit of the latter being traced from battery, through 18, 109, Y^x , 185, 184, 183, 186 and ground. The actuation of this magnet restores the switch X to its original condition.

We will assume that the wanted subscriber's line is not busy. When the wipers t^7 , t^8 come into engagement with the contacts c^7 and c^8 the relay G^z pulls up in series with the cut-off relay of the called subscriber's line, the actuating circuit being from battery B, through 18, 147, G^z , trunk conductor 206, contacts 148 and 149 of the ringing relay X, trunk extension 150, z^3 , t^8 , c^8 , and through the called subscriber's cut-off relay to ground. The pulling up of the called subscriber's cut-off relay connects his line with the extensions leading to the contacts c^7 and c^8 .

The actuation of the relay G^z puts battery current on the ringing relay X, the actuating circuit being from battery B, through 18, 147, 151, armature 152, 153, armature 154 of relay O, 155, X, and through the interrupter I^r to the ground. Owing to the fact that the interrupter I^r is in circuit, the relay X pulls up periodically breaking the switch circuit at the contacts 148, 149 and 156, 157 and connecting the generator G^r through the tip and sleeve sides of the subscriber's line circuit through the closure of the contacts 158 and 159. The ringing of the subscriber's bell takes place therefore by current over one side of the line and back upon the other. When the subscriber answers, the tip relay F^z is actuated, the actuating current of the relay being

over the sleeve side of the subscriber's line in the manner already traced, back upon the tip side and through c' , t' , s' , 160, 156, 157, 207, F^z and ground. This happens of course at an interval when the interrupter has cut off current from the ringing relay X allowing it to fall back and to close the contacts 156, 157. The movement of the armature 161 of the tip relay F^z closes the energizing circuit of the relay O said circuit being from battery through 147, 151, 152, 162, 161, 163, O , 164, through the closed contacts 165 and 166 to ground. It will be noted that the contacts 165 and 166 are closed immediately on the first vertical motion of the shaft S^z of the connector switch. The actuation of the relay O causes the breaking of the actuating circuit of the ringing relay X by the movement of the armature 154. After the relay O has pulled up it is locked the locking circuit being from battery, through 147, 167, 168, 169, O , 164, 165, 166 and ground. Both subscribers are now connected for conversation. The battery supply circuit for the calling subscriber is from battery, through the sleeve relay R^c , over the trunk 100, the sleeve side of the subscriber's line, through his telephone, back upon the tip side over trunk conductor 101 and to ground through the tip relay R^b . The battery supply circuit for the called subscriber is from battery, through the sleeve relay G^z , over the sleeve side of the subscriber's circuit, through his telephone, back upon the tip side, and to ground through the tip relay F^z .

When conversation has ended, the clearing out is accomplished in the system I have used for illustration by the calling subscriber hanging up his receiver. The means by which this is done has already been described in connection with the test circuit of relay W^z of the connector switch. It will be remembered that when the calling subscriber hangs up, the tip relay of the trunk 100, 101, is deenergized and the retraction of its armature 98 puts a simultaneous impulse on both connected trunks which energizes the tip relay D^z and the sleeve relay E^z simultaneously thereby completing the release circuits in the manner already traced.

It will be understood that the release of the switches could be accomplished by the subscriber putting an impulse on the connected trunk wires for simultaneously operating the three pairs of relays when he hangs up his receiver. In fact it is frequently done in practice but I have not deemed it necessary to show means for doing this since the particular invention in the present application lies in the apparatus for effecting the connection of a calling line with an idle trunk and the distribution of the incoming calls.

While I have shown my invention as working in conjunction with automatic switches of the Keith and Erickson type heretofore referred to it will be understood that any automatic switch for effecting a completed connection with a wanted subscriber may be used. Thus, one having a rotary movement for picking out a row of contacts and then a vertical movement for selecting a particular contact of the row might be used. I therefore do not wish to limit myself to the specific form herein shown and shall claim broadly the necessary elements of my invention in combination with any automatic means for effecting a completed connection.

Fig. 7 shows a circuit permitting the employment of a modified form of pilot switch. In the pilot switch heretofore described there are 110 bank contacts, but since the groups of line relays are connected to the row contacts for rotary testing, it is quite evident that cross groups may be similarly connected to common vertical contacts, if suitable provision is made for preventing confusion between the units contacts in different groups if more than one line is calling at the same time. The simplest embodiment of this idea is to have two ten point switches, such as I have shown in my prior application filed April 20, 1907, Serial No. 369,201, the first acting to select the decimal group of lines in which the calling line is to be found, and the second then starting up to pick out the particular line in the group. Since each switch has ten contacts, I may divide the lines into double groups of ten, that is to say lines numbered from 1 to 10 should have their local contacts 31 connected in common through the wire 32 to the first contact of what I may call the tens bank. Similarly lines numbered from 11 to 20 should have their local contacts 31 connected through the common wire 32 with the second contact in the tens bank, and so on. This much of the connection is precisely the same as that shown in Fig. 1 with regard to the "row" contacts. Further than this, however, all the lines having the unit number 1, *i. e.*, 1, 11, 21, 31, etc., should have their relay contacts 46 connected in common to the first contact in what I may call the units bank of the pilot switch. Similarly, all the lines having the unit number 2, *i. e.*, 2, 12, 22, 32, etc., should have their contacts 46 connected through a common wire to the second contact in the units bank, and so on. The result of this cross combination is that if any particular line is calling it will close its relay contacts onto the common tens and common units contact corresponding to the two digits in its number. For example assume that line No. 46 to be the calling line, and it will be plain that its contacts will close onto the wires leading to 130

the 4th tens contact, and the 6th units contact. The operation of the pilot switch is precisely the same as that of the switch P^s in Fig. 1, the differences in the circuit being 5 shown in Fig. 7 and being only those necessary to accommodate the slight change in the character of the switch.

With the above arrangement, in order to prevent interference between lines calling at 10 the same time, I make the tens contacts in pairs, as shown in Fig. 7 so that the battery supply for the units contacts will be fed back through the duplicate tens contacts, and thus only that unit will be selected 15 which is energized in the group to which the tens contact already selected belongs. For example, let us suppose that lines 28 and 46 are calling. Without any special provision being made, and using the two ten point 20 switches referred to, the operation would be as follows: The relay E would pull up, the switch P^u would start up, and come to rest with its wiper on the second contact, this being the lowest number calling. The units 25 switch P^u would then start up and come to rest with its wiper on the 6th contact, this being the first one reached that has battery on it. The result of these conjoined actions is to step up the first idle connector switch 30 S, etc., to the line No. 26 which is obviously neither of those calling. On the other hand, using the twin contacts, this confusion cannot occur, for suppose the same numbers are calling, and the tens wiper has moved 35 around to the second contact. Battery current is then fed back over the duplicate contact to the armature contact 8 of the line relay of line No. 28, and from thence through the common wire to the No. 8 units 40 contact. The units switch P^u starts up and goes around until it reaches the 8th contact, this being the first contact that has battery connected to it. Obviously all the other contacts are dead because only the group of 45 lines numbered from 21 to 30 has battery connected to its line relay contacts 8 as long as the tens wiper is resting on the second bank contact. Of course, if there are two or more lines in the same decimal group 50 calling at once, then the line having the lowest number will be picked out first, as for example the numbers 24 and 28, or numbers 62 and 65, or the like.

In practice I prefer to make the two ten 55 point switches P^s and P^u in a single or common unit, which as shown in Fig. 8 may be described as follows: A base plate carries the tens and units bank contacts and the duplicate tens contacts arranged substantially in the same manner as in my prior application above mentioned in Figs. 5, 6 and 7 thereof. The spindle of the switch extends through the supporting plate, and above the plate a short sleeve is mounted 60 upon it, this sleeve carrying the tens wiper

and its twin which co-operates with the duplicate tens contacts. The sleeve also carries its own ratchet wheel and is turned on the spindle by means of the rotary magnet R^s the same as in Fig. 1 hereof. The spindle has its ratchet wheel below the mounting plate and its operating magnet V^s secured below the plate. The sleeve and the spindle each of them has its own little spiral retracting spring and both the ratchet wheels of sleeve and spindle are engaged by a pivoted detent or dog controlled by a single release magnet mounted on one face of the plate. This magnet is the same as R^s in Fig. 1 hereof. 70

It will be observed that this modified form of switch is merely a duplication of the ten point switch shown in my prior application and as to its general features is well known in the prior art. This combination form, 75 however, I consider to be original with me and shall therefore claim the same both as to its circuit connections and mechanical arrangement thereof. 80

I am aware that many changes and modifications may be made in the circuits and apparatus hereinbefore described without departing from the spirit of my invention which may be stated in broad terms as follows: A pilot switch responding immediately to any calling line in a group to which it is assigned, testing the lines to ascertain which one is calling, and at the same time carrying along with it an idle connector switch, which it leaves in connection with the calling line and then restores itself ready for another call. This arrangement obviously leaves the primary connector switches free from any testing operation, and makes them merely driven switches, positive in 90 their action and in most respects uniform with the ordinary and regular connector switches of the automatic set. 95

In this system it should be noted that all multiplying of the test contacts is done away with and in the special arrangement shown in Fig. 7 even the single set of testing contacts is reduced from 110 down to 20, so that the connections and cabling represent probably the acme of simplicity in this class of 100 work. In some installations it may prove advisable to have the pilot switch in duplicate for each group of trunks and the lines served thereby, each switch having access to the entire group of lines but controlling only one-half of the group of trunks, so that in case of a breakdown in one pilot switch, the other group of trunks would not be disabled; but ordinarily this would probably not be necessary. 110

I contemplate applying this principle of a pilot switch governing concurrently acting connector switches to other purposes than primary selection alone, for example in a number of prior applications I have 120

described and illustrated secondary selector outfits for connecting an idle operator's set to the trunk which in turn has become connected to a calling subscriber's line. Among 5 these applications are serial No. 369,201, filed April 20, 1907; Serial No. 370,051, filed April 24, 1907; Serial No. 383,874, filed July 15, 1907; Serial No. 366,849, filed April 6, 1907; and Serial No. 383,875, filed July 15, 10 1907. In order to use the pilot switch principle in such secondary selection it is only necessary to follow the circuits of Fig. 1, regarding the line relay M therein as a trunk relay which becomes active when the trunk 15 is in service, such as R^c or R^a; and regarding the link circuits 100—101, etc., as operators' circuits, the operators then being connected substantially as shown in Figs. 2 and 3, but without any plug P or extension wires 20 200—201. It is believed that this and other methods of applying the principle I have described will be sufficiently apparent to those skilled in the art without further description or illustration, and it is to be understood that all non-essential variations as 25 well as the several applications of my invention to different uses, are contemplated as within the scope of my claims.

Having thus described my invention what 30 I claim and desire to secure by Letters Patent is:

1. In a telephone exchange system, a plurality of subscribers' lines, link circuits for interconnecting said lines, means for connecting a calling line with any link, and a unitary automatic pilot or selector for said means, common to a plurality of lines and links, containing testing terminals for the lines, and acting in response to a call over 40 any line to automatically select said line and synchronously actuate connecting means to select the same line and connect it with an idle link.

2. In a telephone exchange system, a plurality of subscribers' lines, link circuits for interconnecting said lines, a plurality of automatic means for connecting calling lines with the links, means for distributing the calls among the links, and a unitary automatic pilot or selector common to a plurality of lines and links, containing testing terminals for the lines, and acting in response to a call over any line to automatically select said line and synchronously actuate connecting means to select the same line and connect it with an idle link.

3. In a telephone exchange system, a plurality of subscribers' lines, link circuits for interconnecting said lines, a plurality of automatic connective devices, a unitary pilot switch arranged to select a calling line and means associated with said pilot switch for effecting synchronously with the selection of the calling line the connection of a calling

line to a link through the medium of one of 65 said automatic connective devices.

4. In a telephone exchange system, a plurality of subscribers' lines, link circuits for interconnecting said lines, automatic connective means associated with each link circuit 70 and a unitary pilot switch common to a plurality of said lines and links containing line testing terminals and adapted in response to a call over any line to test said terminals until the calling line is found, and to synchronously actuate an idle one of said automatic connective means.

5. In a telephone exchange system, a plurality of subscribers' lines, a plurality of link circuits for interconnecting said lines, 80 a unitary pilot switch common to said links and arranged to select a calling line, an automatic switch associated with each link and synchronously controlled by said pilot switch for connecting a calling line with a 85 link and means for distributing the calls among the idle links.

6. In a telephone exchange system, a plurality of subscribers' lines, link circuits for interconnecting said lines, a unitary line selecting pilot switch for selecting a calling line common to said links, an automatic primary selector switch arranged to be synchronously actuated with and by said pilot switch, associated with each link, a distributing switch for distributing calls among the idle links and means controlled by a calling subscriber for restoring all of said pilot and primary switches to their normal positions.

7. In a telephone exchange system, a plurality of subscribers' lines, link circuits for interconnecting said lines, a unitary line selecting electro-magnetically actuated pilot switch common to said lines and links, an 105 electro-magnetically actuated automatic primary selector switch associated with each link, a distributing switch for distributing calls among the idle links, with circuit connections for the pilot switch controlled over 110 the subscribers' lines in calling and actuating circuit connections for the primary selector switches controlled by the pilot switch as determined by the distributing switch.

8. In a telephone exchange system, a plurality of subscribers' lines, link circuits for interconnecting said lines, a unitary line selecting pilot switch common to said lines and link circuits, an automatic primary selector switch associated with each link circuit, means for causing the pilot switch to select a calling line and means associated with said pilot switch for causing simultaneous and corresponding movements of the 120 automatic switch associated with an idle link circuit for effecting a connection with the same calling line.

9. In a telephone exchange system, a plurality of line circuits, link circuits for interconnecting the same, a two-motion primary selector switch associated with each link circuit and containing rows of terminals for the line talking circuits only, a two-motion pilot switch common to a plurality of the primary selector switches, containing rows of individual line testing terminals and 5 an additional testing terminal for each row, actuating means for said pilot switch controlled by any line in calling, means also controlled by a line in calling for changing the condition of its individual terminal and 10 also of its row terminal in the pilot switch, and actuating means for the primary selector switches controlled in the movement of the pilot switch, whereby in response to a call the pilot switch will select the row and 15 also the individual contact of the line calling, and will synchronously actuate a primary selector switch to select the talking terminals of the same line and connect them to its associated link circuit.
- 20 10. In a telephone exchange system, a plurality of subscribers' lines, link circuits for interconnecting said lines, means for connecting a calling line with any link, and a unitary automatic calling line pilot selector 25 for said means common to a plurality of said lines and links containing testing terminals for the lines, and acting in response to a call over any line to automatically select said calling line and causing simultaneous 30 selective actuation of said connecting means to connect the same calling line with an idle link.
- 35 11. In a telephone exchange system, a plurality of line circuits to be individually tested for a certain line condition, and a unitary two-motion testing switch responsive to said line condition and to which said lines are connected in groups, said switch being adapted by one motion to find the group to 40 which a given line belongs, and by another motion to find the given line and separate connecting means controlled by said two-motion testing switch for effecting connection with a found line having a given condition.
- 45 12. In a telephone exchange system, a plurality of line circuits to be individually tested for a certain line condition, a two-motion testing switch having certain contacts common to certain groups of said lines, and having also an individual contact for each line, and actuating means for said switch controlled by the condition of the lines for actuating said switch first to move over the 50 group contacts by one motion to find the group of a line, and then to move over the individual contacts to find the individual contact of a particular line of the found group and separate connecting means con-
- trolled by said two-motion testing switch 65 for effecting connection with a found line having a given condition.
- 70 13. In a telephone exchange system, a plurality of line circuits to be individually tested for a certain condition, a two-motion testing switch having certain contacts common to certain groups of said lines, and an individual contact for each line, the individual contacts of each group and the group contact being arranged in a vertical row, and 75 actuating means for said switch controlled by the condition of the lines for actuating said switch first to test from row to row on the group contacts to find the group of a line, and thereafter to move over the individual contacts of the row found to find the individual line having the condition to 80 which the switch is responsive and step by step connecting means controlled by said two-motion testing switch for effecting connection with a found line having a given condition.
- 85 14. In a telephone exchange system, a plurality of line circuits, link circuits for interconnecting the same, a two-motion primary selector switch associated with each line circuit, and containing rows of line talking circuit contacts only, a two-motion calling line selector pilot switch common to a plurality of primary selectors and containing 90 rows of individual calling line testing terminals, and an additional testing terminal for each row, the rows of each said two-motion switches being vertically arranged in 95 horizontal alignment on arcs of circles, a wiper for each of said switches adapted for both rotary and vertical step by step movement, actuating means for said pilot switch controlled by any line in calling for 100 causing the wiper of said pilot switch first to rotate over the row testing terminals of the rows to select the row of the calling line, means also controlled by a line in calling for effecting cessation of said 105 rotary movement upon the finding of a row and causing a vertical movement on the row found, means also controlled by a calling line for stopping the vertical movement upon the finding of the individual calling line contact of the row, actuating means 110 for the primary selector switches controlled in the movement of the pilot switch, whereby the primary selector switches are actuated each to connect with its link the calling line found by the pilot switch, and 115 means effecting the return of the pilot switch to normal after each finding.
- 120 15. In a telephone exchange system, a plurality of subscribers' lines divided into groups, group and individual test circuits associated with said groups and lines respectively, link circuits for interconnecting said lines, connective means associated with 125

each link containing terminals of line circuits only and operated by impulses to connect therewith, and group and individual impulse controlling means common to a plurality of said connecting means and operating in said test circuits during the actuation of said connective means.

16. In a telephone exchange system, a plurality of subscribers' lines, test circuits for said lines, link circuits for interconnecting the same, connective means associated with each link containing terminals of line cir-

cuits only and separate self-contained unitary testing means for said connective means common to a plurality of the same containing terminals of the test circuits only and adapted to test each line upon the connection of said connective means therewith.

In testimony whereof I affix my signature in presence of two witnesses.

EDWARD E. CLEMENT.
